UNITED STATES PATENT OFFICE.

THOMAS A. RILEY, OF CENTRAL FALLS, AND PETER F. HUGHES, OF PAWTUCKET, RHODE ISLAND.

FLY-LEAFING MACHINE.

No. 917,966.

Specification of Letters Patent.

Patented April 13, 1909.

Application filed April 20, 1908. Serial No. 427,985.

To all whom it may concern:

Be it known that we, THOMAS A. RILEY and PETER F. HUGHES, citizens of the United States of America, and residents, respectively, of Central Falls and Pawtucket, in the county of Providence and State of Rhode Island, have jointly invented certain new and useful Improvements in Fly-Leafing Machines, of which the following is a specification.

Our invention relates to novel improvements in machines for automatically affixing fly-leaves or strips of paper to the interior of paper or paste-board boxes. The present fly-leafing machine, so-called, is, however, more particularly devised and adapted for automatically selecting, gluing and affixing a thin fly-leaf or strip of paper along the upper inner edge of one of the side walls or neck of boxes, the latter being suitably positioned on and removed from the machine singly and in an intermittent manner by an attendant.

To this end our invention consists, essentially, of an organized or self-contained machine having means for intermittently coating a glue-bar, so-called, or wiper with an adhesive substance, as paste or glue, from a suitably disposed supply; means for holding a pad of loose fly-leaves with respect to said bar; means for supporting an inverted box in position above the bar and fly-leaves, and devices for transferring glue from the bar to the proximate surface of the box and pressing the latter against the positioned fly-leaves, the result being to evenly and smoothly affix the adjacent leaf to the box, all as more fully hereinafter set forth and claimed.

By means of our invention fly-leaves may be secured to boxes in a more uniform and rapid manner than has been possible heretofore; the work at the same time being effected with greater accuracy, sureness and cleanliness, the latter referring to the fact that the box is not liable to become accidentally spotted or smutched with the adhesive material used while it is being operated upon on the machine.

In the accompanying four sheets of drawings, Figure 1 represents a front or right end elevation of a self-contained power-driven fly-leafing machine embodying our invention, a portion being broken away adjacent the fly-leaf container or holder. The

parts are shown in the normal retracted position, the box, however, being omitted. In this figure the mechanism proper is disposed or inclined at an angle with respect to the base or floor and is also adapted to be operated by a treadle or foot-power. Fig. 2 is a corresponding top plan view, in enlarged scale. In this and the succeeding figures the projections or plane of the views are taken at right angles to the said inclined plane. Fig. 3 is a transverse section taken substantially on line 3 3 of Fig. 2, and immediately preceding the gluing of the box. Fig. 4 is a similar sectional view showing the position of the mechanism while the glued surface of the box is being pressed against the adjacent fly-leaf of the pad. Fig. 5 represents a partial front end elevation, corresponding substantially with the position shown in Fig. 3. Fig. 6 is a similar view, corresponding with Fig. 4. Fig. 7 is a sectional view taken on line 7 7 of Fig. 4. Fig. 8 is a longitudinal sectional view taken on line 8 8 of Fig. 2. Fig. 9 represents a perspective view of a box, and Fig. 10 a similar view showing the fly-leaf affixed to the box.

In the drawings, A Fig. 1, indicates our improved fly-leafing machine as a whole. The operating mechanism proper is mounted on suitable legs *a* provided at the top with flanges *a*¹, *a*², the latter extending rearwardly and upwardly at an angle say of 30°. The front side of the base portion of the machine is extended to form the flat level work table *b*² secured by bolts to said flanges *a*¹; the rear portion of the base *b*¹ is inclined and bolted to the flanges *a*², all as clearly shown.

At or near the back portion of the base are located a pair of laterally separated short standards *b*⁶ forming supports and bearings for the revoluble driving-shaft *s*. See also Fig. 2. This latter has a pulley *p* secured to its front end adapted to receive a driving-belt *p*¹. Between the latter and the front bearing the shaft is provided with a sprocket-wheel *v* carrying a chain *v*¹ for transmitting power to a smaller wheel *v*² fixed to the shaft *v*³ of the main glue-roll *B* which is revoluble in the glue or other suitable adhesive material contained in the reservoir *G*. See also Figs. 3 and 4. The shaft of said roll is mounted to revolve in bearings in the vertical sides *b* of the frame or hous-

ing. To the rear end of said shaft is secured a spur gear g^1 meshing into a similar gear secured to the corresponding end of and driving a smaller roll C. This latter 5 roll is adjustably mounted and is employed to control and gage the thickness of the film of adhesive material to be transferred to roll D and later applied to the glue-bar and the neck of the box.

10 The following is a description of the means represented for controlling and effecting the lateral adjustment of said roll C: The two end portions of the roll's shaft pass freely through elongated openings c^2 , Fig. 3, and revolve in bearings formed in the free ends of members y, in turn supported on pivots y^4 fixed in the vertical sides of frame b. A bolt y^1 is jointed to each member y and extends rearwardly therefrom and 15 through a fixed ear y^2 ; nuts y^3 and y^5 maintaining it in any desired position. As thus devised means are provided whereby the roll C may be set or adjusted in relation to roll B so as to readily and accurately vary the 20 thickness of the glue carried by the latter, as desired.

The front side of the machine, that is at the point where the fly-leaves are affixed to the boxes, is provided with a longitudinally 30 extending vertical pocket or recess R, open at the top, in which is removably mounted the vertically adjustable holder or reservoir E containing the pad or block of superimposed individual units or fly-leaves z supported edgewise therein. As drawn, each 35 end of the holder is provided with a guide or rod z^1 movable therewith and extending downwardly through the base b^1 (Figs. 4, 8, &c.), set-screws z^2 maintaining the holder 40 in the adjusted positions. The holder does not extend above the top face of the table c, although the corresponding edges of the fly-leaves do; in fact the distance that the latter projects above the table practically 45 determines the width of the surface that is to be glue-covered.

Immediately in front of and forming a support or backing for that portion of the fly-leaves extending above the table is located a removably secured bar n^1 , its length 50 being equal to that of the leaves z and also being substantially flush with their upper edges. This bar should always correspond with the length of the leaves. These latter 55 are maintained in position longitudinally or endwise by means of the two thin end gages F resting flatwise upon and being secured to the table c by the clamping bolts f^1 passing through slotted openings f^6 60 formed in the table. The rear ends of these gages extend transversely across the said pocket R and over the vertically movable yieldingly mounted glue-bar carrier member m, soon to be described; the top edge or 65 face of the latter when in the normal ele-

vated position being substantially level or even with that of table c. The said member m is as shown comparatively wide and is fitted to move vertically in recesses e formed in the two end members of the frame b. 70 See also Figs. 5 to 8. It is provided with a pair of vertical tie-rods e^2 , each having a helical spring e^1 arranged to press the member m upwardly. The glue-bar n, above referred to, is substantially the same in form 75 and size as the bar n^1 . It is secured to the top of carrier m and projects therefrom laterally a short distance toward the rear. To the rear side and near each end of member m is fixed a vertical cam-shaped projection r disposed just outside and contiguous to the side frames b; these cams in cooperation with the two swinging arms i pivoted at i^1 to said frame are adapted to contact with the lower end i^2 of said arms and swing 80 the upper portions of the latter a short distance toward the front whenever the member m is depressed to its limit. See Fig. 6. The object of this arrangement is to temporarily lock the freely revoluble transfer 85 glue-roll D in position while the member m in its upward movement causes the face of the glue-bar n to contact with the surface of the roll and receive therefrom a thin coat of glue preliminary to gluing the next 90 box. See Figs. 4 and 6. The roll D is journaled in said arms i, its shaft i^4 extending through elongated openings i^3 formed in the side frame. Springs r^2 engaging the lower portion i^2 of the arms operate to swing 100 the roll rearwardly to contact with the surface of the continuously revolving main glue-roll B when the member m carries said cams upwardly past the arms. See Fig. 5. 105

The upper portion of each side frame b is provided with ears b^3 having a horizontal guide-rod b^4 secured thereto. A cross-head d is mounted transversely of and slidable on said rods. The former extends transversely of the machine and is jointed at each end to a knee-lever f secured to a mechanically actuated rock-shaft g mounted in ears f^4 depending from the base b^1 . As thus arranged the guided cross-head reciprocates back and forth in one plane by means of the levers f, the ends of the latter being slotted to allow for the versed sine of the arc through which the levers move. A presser-bar h is also slidably mounted on 110 said rods b^4 , the same being arranged parallel with and located in front of the cross-head. The member h is resisted or pressed by helical springs d^1 interposed between the parts d and h. The latter is connected to and actuated by the cross-head through the medium of flat links h^1 having slotted apertures h^2 therethrough so as to provide for a degree of lateral movement independently of that imparted to it by the cross- 115 120 125 130

head. The front or working side of the presser-bar may be provided with a longitudinally extending strip h^4 of rubber or other material having a degree of elasticity and compressibility. See Figs. 2, 3 and 7. When in action the said face of the bar h is adapted to engage the outer face of the neck portion n^4 of the positioned inverted box H and press the latter toward the front 5 until its inner surface bears snugly against the adjacent glue-coated surface of the glue-bar n carried by the vertically movable plate member m . At or near each end of the latter is secured a dog or lug m^1 , the same 10 extending a short distance above the top face and normally above the plane of the lower side of the presser-bar. The face of the lugs are arranged and positioned with respect to the working face of said bar so 15 that the latter will engage the lugs and not the glue-bar in case a box be omitted, thus positively preventing the glue-bar from contacting with and smearing the presser-bar.

20 The mechanism for actuating the rock-shaft g comprises a crank-disk h secured to the rear end of the main driving-shaft, a crank-pin s^1 fixed to the disk at a proper distance from the center to give the desired stroke to the cross-head, a lever s^3 fixed to shaft g , and a link s^2 , extending through an opening h^1 formed in base b^1 , jointed to said crank-pin and lever.

25 Assuming now that the several devices 35 have been adjusted or positioned and properly timed with relation to one another, the reservoir G charged with glue or other suitable adhesive material, the pad of loose superimposed fly-leaves or units z placed in the holder E and the gages F positioned close to the ends of the pad, and having the cross-head, &c., at the rear end of the stroke, or 40 dead center, substantially as represented in Figs. 1, 2 and 3, the manner of operation of our improved fly-leafing machine may be 45 described as follows: Now upon starting the machine, see arrow direction Fig. 1, the revolving geared glue-rolls C and B operate to transfer a portion of the film of glue direct from the surface of the latter roll onto the laterally movable transfer-roll D then 50 contacting therewith. While the cross-head is now advancing on its forward stroke the working face of the presser-bar h engages 55 with and is arrested by the said end lugs m^1 of the then normally elevated carrier member m , thus preventing actual contact with the glue-bar n , a box H not being in position. The continued forward movement of the 60 cross-head's operating levers f , the shorter arms f^1 of the latter and the screw-threaded rods f^2 jointed to the member m and passing freely through the free ends of said arms, next operate to depress the member m , 65 thereby at the same time causing the cams r thereof to swing the glue-transferring roll D away from the roll B to the forward temporarily stationary and locked position, the further and final movement of the operating levers forcing the member m downwardly to its limit, thereby, too, at the same time carrying the lugs m^1 below the bar h and wiping the working face of the glue-bar n against the surface of the roll D . Fig. 70 3 represents the corresponding position of the parts. At the instant the bar h is thus released the springs d^1 of the still advancing cross-head act to press the member h ahead to its limit. If the holder E is supplied with the fly-leaves z the latter will arrest the 75 bar's movement, otherwise the bolts h^5 passing through the slots h^2 of the links h^1 will constitute the stop. Upon the return stroke of the cross-head, &c., the springs e^1 elevate the carrier m until its lugs m^1 contact with the underside of the then rearwardly moving presser-bar, the glue-bar n at the same time again taking glue from the roll D . At the instant the bar h slides past the lugs m^1 80 the springs e^1 force the member m upwardly 90 to its limit of movement, thereby withdrawing the cams r from the roll-carrying levers i and permitting the springs r^2 to swing the roll D back to its normal position against the surface of the main roll B to be recharged with a film of glue, substantially as 95 shown in Figs. 3 and 5. The operator now positions an inverted box H upon the gages F of the table c so that the side wall portion of the neck n^4 (to the inner face of which 100 the fly-leaf is to be affixed) will be interposed in the then open space formed between the adjacent faces of the presser-bar and glue-bar. See Fig. 3. The cross-head 105 now in its advancing stroke causes the bar h to yieldingly engage the said neck portion of the box and press it bodily along until its inner surface bears evenly and firmly against the glue-covered face of the glue-bar n . Fig. 5 represents the corresponding position. The further movement of the rock-shaft, &c., advances the roll D into position, depresses carrier member m , and causes the 110 face of the bar n to slide downwardly past the neck of the box, thereby at the same 115 time wiping off or transferring the glue from the bar onto the said inner surface of the contiguous neck portion of the box. At this instant the now released presser-bar immediately acts to push the box ahead 120 bodily until it is arrested by the pad of fly-leaves, the resilient force operating through the bar h causing the upper or, as drawn, the rearmost fly-leaf to become evenly and securely affixed to the glued surface of the 125 box. Figs. 4 and 6 represent the corresponding position. Meanwhile the member m completes its downward stroke and is returning upwardly while the presser-bar is 130 being retracted from actual contact with the

box; at the same time too the glue-bar is being re-coated with a film of glue, as before described. At the completion of the operation the relation of the several parts will be substantially as shown in Figs. 1 and 2, the machine being in intermittently continuous action. The attendant now removes the box with its affixed fly-leaf from the machine and places another box H in position as before, between the presser-bar and glue-bar, to be acted upon during the next revolution of the driving-shaft. It is obvious that as the pad of fly-leaves in the holder E becomes gradually reduced in thickness during the fly-leaving operation the presser-bar automatically adapts itself to such variations by means of the springs d¹ so that the efficiency of the machine is maintained at all times, even though a few or only one leaf be present in the holder.

We may add that we prefer to make the length of the glue-bar n just equal to or slightly less than the length of the box interiorly, thus providing means for accurately 25 positioning or centralizing the boxes. The front bar n¹ is a little shorter than the glue-bar, as indicated in Fig. 2. In order to prevent the bar n from applying glue to the extreme corners of the box the vertical ends 30 of the bar are cut away or beveled, substantially as shown in Fig. 2 at n³. In fact the leaves z are usually shorter than said bar, as shown in said figure.

In some cases it may be desirable to operate the machine manually or by treadle-power. In order to accomplish this we have shown in Fig. 1 means well adapted for the purpose. That is to say, the rock-shaft g has a lever w secured thereto to the free end 40 of which latter is attached a cord or flexible connection w¹, the same passing over a carrier wheel w² mounted on a fixed stud w³ and finally attached to the rear or free end of a treadle-lever w⁴, fulcrumed at w⁵ to 45 the legs a. Upon depressing the treadle the cross-head will be advanced and the co-operating parts actuated substantially as before described. In order to return said members back to the normal position weights 50 w² may be attached to and suspended from the free end of lever s² by means of a connection w¹, as clearly indicated by dotted lines in Fig. 1. It may be added that obviously when the machine is being run by belt power 55 the said treadle and weight connections are first detached from the respective members w and s³. Conversely, the link s² should be disconnected from the crank-pin s¹ while the machine is being operated by foot power. 60 If desired the shaft s may at the same time be rotated to drive the glue-rolls B and C.

In Fig. 1 we have represented the mechanism constituting the major part of our improved fly-leaving machine mounted at an 65 angle or inclined to the plane of the floor.

An advantage resulting from this arrangement is that the fly-leaves z in the holder or container maintain themselves in proper position by gravity; that is to say, the overbalanced weight of the pad of leaves insures that it will lie at all times against the front side of the holder. We may further add that without departing from the spirit of our invention other means or modes of applying the principle of the invention may 70 be used in lieu of those represented, provided of course that such substitute means employed be the equivalent of the means embodied in the subjoined claims.

We claim as our invention and desire to 80 secure by United States Letters Patent:—

1. In a fly-leaving machine provided with a work table or analogous surface, the combination of means adapted to support and position a pad of loose fly-leaves in a vertical or nearly vertical position so that the upper edge portion thereof will extend above said table, a device for applying a film of adhesive material from a source of supply to the inner surface of one side of an inverted box while the latter is temporarily supported on said table in a substantially horizontal position over said pad of fly-leaves, and means for advancing the box so as to cause its adhesive-coated surface to 90 engage the upper edge portion of the proximate fly-leaf, thereby affixing the latter to the box.

2. In a fly-leaving machine provided with a holder for the fly-leaves, and a glue-distributing device, a suitably mounted movable glue-bar arranged to receive a coating of glue from said glue-distributing device, means for transferring or wiping glue directly from the bar to the adjacent surface 100 of a box positioned with relation thereto, and a device for effecting the engagement of the thus-coated surface of the box with the positioned fly-leaf, for the purpose set forth.

3. In a fly-leaving machine, the combination with a holder for containing the fly-leaves, a movable glue-bar or analogous device, and means for applying a coat of glue or other suitable adhesive material thereto, of a movable resilient presser-bar for temporarily clamping between the working faces of said bars one of the side walls or neck of a suitably positioned box, means for withdrawing the glue-bar whereby its coat of glue is transferred or left upon the adjacent surface of said side wall of the box, and means co-operating with the presser-bar for causing the thus glue-coated surface of the box to snugly contact with the proximate fly-leaf while the glue-bar is being re-coated 115 with adhesive material.

4. In a fly-leaving machine, the combination with means for supporting a pad of vertically disposed fly-leaves, and a vertically movable glue-bar located in front of 120

- and a short distance from said pad, of means for coating the glue-bar with a film of glue or adhesive material, means for moving said glue-bar downwardly whereby it is adapted 5 to wipe its said adhesive material directly therefrom onto the inner surface of one side of a suitably positioned box, and means for pressing the thus adhesive-coated surface of the box against the proximate fly-leaf.
- 10 5. In a fly-leaving machine, the combination of a presser - bar and a glue - bar arranged for movement in planes at substantially right angles with each other, means for actuating said members in the respective 15 planes so that when in use the wall of a properly positioned box may be clamped between the adjacent or working faces of the bars, and a device for positively preventing the actual contact of the said working faces 20 of the bar members in case a box be omitted or unpositioned between them.
6. In a fly-leaving machine, the combination with a holder for containing a vertically disposed pad of loose fly-leaves, means 25 for applying adhesive material to the inner surface of one side of an inverted box positioned over the holder and fly-leaves, and a stationary resisting bar or member for supporting the upper edge portion of the 30 pad, of adjustably mounted gage members for positioning the fly-leaves endwise in said holder, and a device for advancing the box and yieldingly pressing its adhesive-coated surface against the proximate fly-leaf, for the purpose set forth.
7. In a fly-leaving machine, the combination with a suitably guided cross-head, a spring-pressed bar member capable of limited independent movement connected therewith, and means for reciprocating the cross-head, of a glue-bar movable in a plane disposed at an angle to that of the cross-head, means for applying glue to the working face 40 of the glue-bar, and a holder for containing a pad of positioned fly-leaves whose upper edge portions project in the path of the said presser - bar, all constructed and arranged whereby the conjoint action of said presser and glue-bars upon the neck of a 45 box placed therebetween maintains it in frictional contact with the glue-bar while the
- latter is applying glue to the neck's surface, the final action of the presser-bar causing the thus-glued surface of the box to engage the proximate fly-leaf and affix it 55 thereto.
8. In a fly-leaving machine, the combination with a fixed bar n^1 extending transversely across the front end of the machine, and a holder for containing fly-leaves arranged so that when in use the upper edge portion of the latter project above the holder and are resisted by said bar, of means for centralizing and positioning an inverted box with relation to the said bar and upper 60 portion of the fly-leaves, means for applying paste to the inner surface of one of the walls of the neck of said positioned box, and means for advancing the box so as to cause its paste-coated surface to yieldingly engage the adjacent portion of the proximate fly-leaf.
9. In a fly-leaving machine, the combination with a positively revoluble main glue-carrying roll, a transfer-roll, and means for 65 intermittently moving the latter into engagement with and disengagement from the surface of the main roll so as to receive thereon a coating of glue, of a vertically movable spring-pressed carrier member arranged parallel with said rolls, a glue-bar secured to and movable bodily in a vertical direction with said carrier member having a face thereof adapted to frictionally engage the surface of the transfer-roll and be 70 coated with glue from the latter while the machine is in action, a horizontally movable presser-bar for holding an open box in position against the glue-bar while the latter is transferring glue therefrom onto the wall 75 of the box, means for positioning a fly-leaf in the path of said presser-bar, and means cooperating with the presser-bar for causing the engagement of the thus coated surface of the box with said fly-leaf.

Signed at Providence, R. I., this 18th day of April, 1908.
